UNITED STATES PATENT OFFICE.

ANDREW H. CANDEE, OF PITTSBURGH, PENNSYLVANIA, ASSIGNOR TO WESTINGHOUSE ELECTRIC & MANUFACTURING COMPANY, A CORPORATION OF PENNSYLVANIA.

CONTROL DEVICE.

Application filed December 10, 1919. Serial No. 343,986.

My invention relates to control devices and it has special relation to the acceleration of an electric railway motor, for example, by means of an apparatus that is operated on a variable time basis.

One object of my invention is to provide an apparatus of the above-indicated character which shall be relatively simple in construction and reliable in operation to produce the desired result of gradually excluding an accelerating resistor from circuit without requiring current relays or equivalent devices.

More specifically stated, it is the object of my invention to provide a continuously rotatable cam of different transverse cross-sections for actuating a switch member into its closed or resistor-short-circuiting position, the relative periods of actuation to, or 20 retention in, the closed position being varied by longitudinal shifting of the cam.

Other objects of my invention will become evident from the following detailed description taken in conjunction with the accompanying drawing, wherein—

Figure 1 is a diagrammatic view of a control system embodying my present invention; and

Fig. 2 is a view showing another elevation of my control apparatus and certain operating electrical connections therefor.

Referring to the drawings, the system here shown comprises suitable supply-circuit conductors trolley and ground; a dynamo-electric machine, such as a car-propelling motor, having a commutator-type armature A1 and a series field winding F1, the usual reversing switch 1 being provided for determining the direction of operation of the motor; and an accelerating resistor 2, preferably of the inductive type, that is connected in series relation with the dynamo-electric machine to be intermittently short-circuited by a control device 3 that is operated by a small electric motor 4.

The control device 3 comprises a stationary contact tip or terminal 5 that is mounted upon a support or bracket 5a, and a co-operating movable contact tip or terminal 6 that is secured to one end of an oscillatable arm or lever 7, the other end of the lever being biased toward the illustrated position by means of a helical spring 8, and the lever being pivotally mounted at an in-

termediate point 9 upon a rocker arm or lever 10. Preferably a magnetic blowout coil of a familiar type (not shown) is provided in connection with the co-operating contact members. The outer end 11 of the rocker arm 10 is pivotally mounted upon a second support or bracket 12. A roller 13, or the like, is pivotally mounted near the lowermost point of the rocker arm 10 to engage a cam 14, the operating shaft 15 of which is driven by a small electric motor 4 having a commutator-type armature 16 and a shunt field winding 17, the degree of energization of which may be varied by a resistor 18.

The brackets or contact supports 5a and 12 are connected to the respective terminals of the accelerating resistor 2 by conductors 19 and 20.

In addition to the rotative movement of the cam 14 that may be produced through the agency of the electric motor 4, the cam is adapted for bodily longitudinal shifting or actuation and this result may be accomplished, as illustrated in Fig. 2, by means of an actuating coil 21 which encloses a portion of a sleeve 22 that is rigidly secured to the cam body 14 and is adapted to loosely slide along the cam shaft 15, although the rotative movement of the cam with the shaft is insured by the provision of a key 23 that is inserted in the shaft.

For the purpose of energizing the actuating coil 21, a battery 24 may be connected in circuit with the coil through a hand-operated switch 25, which also closes the circuit of the auxiliary motor 4 through the battery. To prevent too rapid longitudinal actuation of the cam 14, a dash-pot 26 is suitably connected with the slidable sleeve 22, whereby a relatively slow longitudinal movement of the cam 14 and, therefore, a desirably smooth acceleration of the main motor is insured. Return movement of the cam 14 to the illustrated normal position is ensured by a biasing spring 27.

As indicated by the various section lines AA to EE, inclusive, the contour of the cam 14 gradually increases in size from one end to the other of the cam, a comparatively sharp point or narrow ridge 14a extending to the peripheral bounding line of the cam at one end thereof, while this ridge gradually increases in size or, in other words,

covers a greater portion of the peripheral line, when approaching the other end of the cam member.

In the illustrated position of the cam, therefore, the rocker arm 10 occupies its lowest position corresponding to the full open position of the movable contact tip 6. Upon rotative movement of the cam 14, the roller 13 will ride along the periphery thereof and, when the ridge 14a passes under the roller 13, a contact of short duration will be effected between the stationary and movable contact tips 5 and 6, respectively. A continuous rotation of the cam 14 by the electric motor will effect periodical short-circuits of the accelerating resistor 2, of short duration, so that the effect of a comparatively great resistance is produced in the circuit of the main or car-propelling motor.

By longitudinally shifting the cam 14 towards its positions of greater cross-section, the duration of the individual short-circuits, which continue to occur periodically, is gradually increased until, when the other end of the cam 14 engages the roller 13, a permanent short-circuit of the resistor 2 is produced. In other words, by continuously rotating the cam 14 and shifting it longitudinally during such rotative movement, the effective or active circuit value of the accelerating resistor 2 is gradually decreased to substantially zero, and thus a smooth acceleration of the main motor may be automatically effected without requiring the use of current relays or the like.

The operation of my system and apparatus may be set forth as follows. With the roller 13 occupying its normal position at the end of the cam 14 of smaller cross-section, as indicated in solid lines in Fig. 2, the switch 25 may be closed to concurrently energize the auxiliary motor 4 and the actuating coil 21. In this way, the movable contact tip 6 is intermittently brought into engagement with the stationary contact tip 5, as previously described, by reason of the rotative movement that is imparted to the cam 14 by the auxiliary motor 4, while the energization of the actuating coil 21 serves to effect a longitudinal shifting of the cam 14 towards the position wherein the greatest transverse cross-section thereof is brought into engagement with the roller 13. Consequently, the duration of the individual

short-circuits of the accelerating resistor 2 gradually increases as the cam is longitudinally shifted until, in the limiting position of the cam, a permanent short-circuit of the resistor is effected, as previously mentioned.

In other words, the action of the cam tends to set up a pulsating current, the amplitude of the pulsations varying as a function of the time that the contact members are in closed position. However, the provision of an inductive resistor, as previously mentioned, or of sufficient inductive characteristics in the motors and other circuits, will serve to smooth out the pulsations.

It will be appreciated that other means of providing simultaneous movements of translation and rotation, such as the screw-threaded shaft and traveling nut that is used in limit switches for elevator control, may be employed, if desired. Consequently, I do not wish to be restricted to the specific circuit connections, structural details or arrangement of parts herein set forth, as various modifications thereof may be made without departing from the spirit and scope of my invention. I desire, therefore, that only such limitations shall be imposed as are indicated in the appended claims.

I claim as my invention:

1. A control system comprising a movable switch member, a resistor adapted to be short-circuited by said switch member, an axially tapering cam for actuating said member, and electrical means for concurrently rotating and longitudinally shifting said cam.

2. In a system of acceleration, the combination with an electric motor and a resistor, of electrically controlled cam means for intermittently modifying the circuit connections of said resistor and for varying the periods of intermittence.

3. In a system of acceleration, the combination with an electric motor a source of energy and a resistor, of continuously rotatable means for periodically shunting said resistor and means electrically governed by said source for varying the time between such shunting actions.

In testimony whereof, I have hereunto subscribed my name this 25th day of November 1919.

ANDREW H. CANDEE.
